PICKUP GAME PIECE

Clyde L. Anderson, White Bear, Minn., assignor to Gould-Cargill & Company, Inc., Minneapolis, Minn., a corporation of New York

Filed Mar. 28, 1968, Ser. No. 11,181

Term of patent 14 years

U.S. Cl. D34—15
Int. Cl. D21—01

FIG 1

The side not shown is a mirror image of that shown in FIGURE 1.

I claim:

The ornamental design for a pickup game piece, as shown and described.
